REED FOR MUSICAL INSTRUMENTS

Henry T. Prescott, Chicago, Ill.

Application February 20, 1933, Serial No. 657,602

9 Claims. (Cl. 84—383)

This invention relates to reeds for musical instruments and more particularly to the provision of a reed adapted for use in connection with the mouthpiece of a saxophone, clarinet, or similar musical instrument.

An object of the invention is to provide an improved reed.

A further object is to provide a reed capable of producing sounds of improved quality.

10 A further object is to provide a reed that has its marginal edges free.

A further object is to provide a reed having an increased or extended marginal vibrational area.

15 A further object is to provide a reed which emits sound-waves having a wave form that produces musical sounds of improved quality.

A further object is to provide a reed that avoids the binding of the marginal portions of the reed when a ligature or other fastening means is 20 clamped around the reed to hold it on the mouthpiece.

25 A further object of the invention is to provide a reed having a greater freedom of vibration without sacrificing the sturdy backbone essential to provide the necessary resiliency or resistance.

30 A further object of the invention is to provide a reed which prevents the means clamping the reed to the mouthpiece from interfering with the free vibration of the reed.

35 A further object is to provide a reed which will in comparison with ordinary reeds emit a sound wave of greater amplitude with a given expenditure of energy or will emit a sound wave of the same amplitude with the expenditure of less energy.

Other objects and advantages of the invention will appear as the description proceeds.

40 A complete understanding of the invention may be had by reference to the following description taken in conjunction with the accompanying drawing in which:

Fig. 1 is a top plan view of a preferred embodiment of the novel reed;

45 Fig. 2 is a side view of the reed shown in Fig. 1;

Fig. 3 is a transverse sectional view taken on the line 3—3 of Fig. 1, on an enlarged scale of the reed shown in Figs. 1 and 2;

Fig. 4 is a view similar to Fig. 3 of a modified embodiment of the reed of the present invention;

50 Fig. 5 is a top plan view of the improved reed shown clamped to a saxophone mouthpiece;

Fig. 6 is a cross section on the line 6—6 of Fig. 5.

55 Referring to the drawing, and more particularly to Figs. 1 to 3, the novel reed is formed with

a rear thick portion 1 and a front portion 2 tapering into a flexible tip.

The bottom portion 3 of the reed is flat so that when the reed is applied to a mouthpiece 4 it will fit tightly against a correspondingly flat surface 5 formed on the mouthpiece 4.

The upper rear portion 1 of the reed is arcuate in shape so that it can be clamped to the mouthpiece 4 by a fastening means such as the ligature 6 shown in Figs. 5 and 6.

10 The reeds now in common use are formed as described above and have their upper rear portions curved from one of their longitudinal edges to their other longitudinal edge with the result that the ligatures or clamping means press the 15 marginal edges as well as the central portions of the rear portions of the reeds tightly between the inner surfaces of such ligatures or clamping means and the top flat surfaces of the mouthpieces.

20 In accordance with the present invention an improved novel reed is formed by constructing the reed in such a manner that when it is clamped to the usual mouthpiece by the usual clamping means the marginal edge portions of the reed will 25 be free to vibrate.

In the embodiment of the invention shown in Figs. 1, 2 and 3 this is accomplished by cutting a substantially crescent-shaped recess or channel 10 in the marginal edge portions of the reed.

30 This recess 10 is preferably cut deep enough so that the thickness of the marginal edges 11 are substantially equal to the thickness of the marginal portions of the reed that prevails at substantially one-quarter of the distance from its 35 tip 7 to its end 8.

The width of the recess 10 is preferably substantially equal to the thickness of the thickest part of the reed, but may be varied within limits determined by the improved quality of sound obtained by extension of the vibrational area of the reed without sacrificing the sturdy backbone of the reed.

40 The depth of the recess 10 may also be varied within certain limits depending on several factors, for example, the dimensions of the particular reed, the kind of cane used, the length of the flexible tip, whether the reed is to be of soft, medium or stiff grade, etc.

45 The particular shape or form of the recess may likewise be varied without departing from the spirit and scope of the present invention, for example, instead of making the marginal recess substantially curve-shaped as illustrated in Fig. 55

3 the recess may be made substantially rectangular like the recess 12 illustrated in Fig. 4.

In the reeds now in use the vibration is confined to the marginal portions of the flexible tip, 5 that is, those portions of the tip outside of the dotted line 9 shown in Fig. 1. Since the reeds now in use have their rear portions curved so that the clamping means bind their longitudinal edges, the vibration of these reeds is confined to 10 the portion of the reed in front of the thicker portion 1, that is the flexible tip portion 2.

I have discovered that reeds of this type can be given greatly improved characteristics by forming a channel or recess 10 or 12 in the 15 marginal portions of the reed. This recess or channel 10 or 12 changes the wave-form of the sound-wave emitted by the reed and thereby improves the quality of the tones emitted.

These recesses 10 or 12 prevent the clamping 20 means from damping the vibrations set up by the edge portions of the flexible tip and as a result fuller improved quality tones are emitted by the reed. In addition with a given amount of energy expended in setting the reed vibrating at 25 a given frequency, the amplitude of the emitted sound-wave will be greater in the case of the improved reed than in the case of reeds now in common use. This reduces fatigue in playing the musical instruments employing my improved 30 reed to a minimum, permits the player to play better in tune, obtain a better tone, and obtain the necessary volume with less effort.

Fig. 5 shows the improved reed applied to the 35 usual saxophone mouthpiece by means of the usual ligature.

Fig. 6 is a cross section on the line 6—6 of Fig. 5, and clearly illustrates how the recesses 10 or 40 12 of the present invention avoid binding of the marginal portions or edges of the reeds which would otherwise occur when the ligature is clamped about the reed to hold it in place on the mouthpiece 4. It is clear from these figures that the channels or recesses 10 or 12 release the marginal side portions of the reed so that there can 45 be no interference with the free vibration of the marginal edges of the reed, and at the same time these channels or recesses 10 or 12 leave a sturdy backbone extending substantially from the end 3 to the tip 7 of the reed to insure good resistance or resiliency while attaining this free vibration.

The embodiment of the invention herein described and illustrated is merely a convenient 50 and useful form of the invention which is capable of many other modifications without departing from the spirit and scope of the invention, which is to be limited only by the scope of the appended claims.

I claim:

60 1. A reed for a saxophone, clarinet or similar musical instrument, comprising a thick portion for supporting the means for clamping the reed to a mouthpiece therefor, a flexible tip portion tapering from said thick portion, and a thin portion at each side of the thick portion co-extending therewith back from said tip portion, the

upper surfaces of said thin portions being spaced a substantial distance from the reed clamping means.

2. A reed for a saxophone, clarinet or similar musical instrument, comprising a thick portion 5 for supporting a ligature for clamping the reed to a mouthpiece, a flexible tip portion, a tapering portion between said tip portion and said thick portion, and recessed marginal portions at each side of said tapering portion and said thick portion and spaced from said ligature, said marginal portions and said flexible tip portion constituting the vibratile area of the reed.

3. A reed for a saxophone, clarinet or similar musical instrument, comprising a thick portion 15 cooperable with a ligature for clamping the reed to a mouthpiece, a flexible tip portion extending from said thick portion, and longitudinal recessed portions at each side of said thick portion and spaced from said ligature when the reed is 20 clamped to said mouthpiece to provide a free vibratile portion at each side of said thick portion.

4. A reed for a saxophone, clarinet or similar musical instrument, comprising a relatively rigid 25 thick portion tapering into a flexible tip portion, and recessed portions at each side of said thick portion forming thin vibratile margins substantially co-extensive with said thick portion for increasing the vibrational area of the reed. 30

5. A reed for a saxophone, clarinet or similar musical instrument, having a curve-shaped recessed portion in each of its longitudinal parallel 35 side margins, said recessed portion having its upper surface spaced a substantial distance from the ligature for clamping the reed to a mouthpiece.

6. A reed for a saxophone, clarinet or similar musical instrument comprising a thick portion adapted to support a ligature, a rectangular-shaped recessed portion constituting each of the longitudinal side margins of said thick portion and spaced from said ligature for freeing the marginal portions of the reed from said ligature. 40

7. In a mouthpiece for a saxophone, clarinet 45 or similar musical instrument having a reed clamping ligature, the combination of a reed having a tip portion and recessed portions spaced a substantial distance from said ligature to form elongated vibratile members extending rearwardly from said reed tip portion at opposite sides of the reed whereby the longitudinal margins of the reed are released from the clamping effect of the ligature.

8. A reed for a saxophone, clarinet or similar 55 musical instrument, comprising a portion for co-operation with the ligature, a flexible tip portion and a pair of ligature-released portions at each side of said first-mentioned portion.

9. A reed for a saxophone, clarinet or similar 60 musical instrument, comprising a portion for supporting a ligature, a flexible tip portion and ligature-released portions concave in shape and located at the longitudinal margins of the reed for freeing said margins from said ligature. 65
